UNITED STATES PATENT OFFICE.

GEORGE FOWLER, OF PHILMONT, NEW YORK.

LATCH.

SPECIFICATION forming part of Letters Patent No. 298,839, dated May 20, 1884.

Application filed March 15, 1884. (No model.)

To all whom it may concern:

Be it known that I, GEORGE FOWLER, a citizen of the United States, residing at Philmont, in the county of Columbia and State of New 5 York, have invented certain new and useful Improvements in Door and Gate Latches and Catches; and I do hereby declare that the following is a full, clear, and exact description of the same, reference being had to the annexed drawings, making a part of this specification, and to the letters and figures of reference marked thereon.

My invention relates to latches intended for use on doors and gates.

15 It consists in a latch having its point or locking end arranged out of line with its shank, and in the combination, with said latch, of the several other parts, as will be hereinafter more fully described and claimed.

20 In the drawings, Figure 1 is a perspective view of a section of a door provided with my latch, and Fig. 2 is a plan view of the latch.

The door A is provided in its outer or swinging edge with a mortise, a, over which, on the 25 edge of the door, is secured the guard-plate B. This plate is provided at about its middle portion with a slot, b, for the passage of the point of the latch, and this slot is elongated vertically to permit the movement of said 30 latch in the operation thereof, as will be described.

The latch C is bent to form the shank c, the arm or connection c', bent from the forward end of the shank, and the point c'', carried forward from the end of the arm c' parallel to, but in a different vertical plane from, the shank, as clearly shown.

In applying my latch its rear end is pivoted to the side of the door or gate, its arm c' is 35 bent laterally into the mortise a, and the point c'' is carried thence forward through the slot in the guard-plate and into position to engage the notched plate secured on the inner side of

the door-jamb or jamb-post, as will be understood from the dotted lines in Fig. 1. By this 45 arrangement I dispense with the loops or keepers required to support the movable ends of latches of ordinary construction, and also provide for the arrangement of the notched or other suitable catch-plate off the face of the 50 door-jamb or jamb-post and on the side thereof, out of the way.

It is manifest the shank may be pivoted in various ways on the gate or door; but in manufacturing the device for use on doors it is preferred to make it with a sleeve or collar, d, on its rear ends, having formed through it an angular opening, which is slipped on the spindle D of the knob, and rigidly secured in place by a set-screw, or in other desired manner. Obviously my latch does not require a knob for its operation; but when used on doors I prefer to employ a knob, as shown and before described.

This latch may be made at slight cost, is 65 easily applied, and is simple and efficient in operation, as set forth.

Having thus described my invention, what I claim, and desire to secure by Letters Patent, is—

The combination, with a door or gate provided in its swinging edge with a mortise, and the guard-plate secured on said edge over said mortise, and provided with a vertical slot, of the latch having its shank pivoted at one end 75 on the door and its other end bend laterally into the mortise, and the point or latching end projected thence through the slot in the guard-plate, substantially as set forth.

In testimony that I claim the above I have 80 hereunto subscribed my name in the presence of two witnesses.

GEORGE FOWLER.
